DRAFTING INSTRUMENT CHUCK AND
WRENCH

Vard B. Wallace, Sierra Madre, Calif., assignor
to Vard Mechanical Laboratory, a copartnership
composed of Vard B. Wallace and Paul H. Ford

Application April 10, 1939, Serial No. 266,967

4 Claims. (Cl. 33—79)

My invention relates to drafting machines and has particular reference to an instrument chuck and wrench for use with drafting machines which finds particular utility when employed as a means 5 for detachably securing one or more interchangeable instruments to a drafting machine head.

Drafting machines ordinarily comprise a parallel mechanism cooperating with a fixed support in such manner as to permit movement of a head 10 portion over a drawing surface in such fashion that the angular position of the head portion relative to any predetermined base line on the drawing board is maintained at a constant value.

The head portions of such drafting machines 15 are ordinarily provided with a means for holding various drafting instruments, such as scales, straight edges, rulers, or similar instruments. Because a different type of instrument is required for different types of drafting operations and different phases of a particular piece of drafting work, these instruments are detachably secured to the drafting machine head by providing a 20 tapered chuck receptacle in the head portion of the machine and a similarly tapered member secured to each of the instruments so that the 25 tapered member may be forcibly inserted in the tapered receptacle to secure the instrument to the drafting machine head.

This type of construction, while providing the 30 advantages of interchangeability of instruments, has the outstanding disadvantage in that the instruments are apt to work loose from the head so that inaccurate work is done with the machine. This may be avoided by forcing the member into 35 the tapered receptacle sufficiently tightly to prevent the working loose of the instrument from the head, but if this is done the wedging action between the tapered surfaces holds the instrument so securely as to make it very difficult of removal.

It has also been found that attempts to forcibly 40 insert the chuck member in the chuck receptacle sometimes gives rise to damage to the instrument or to the drafting machine head, and similarly, attempts to pry the member out of the 45 receptacle once it has become firmly wedged therein, also gives rise to considerable damage to the instrument.

It is therefore an object of my invention to 50 overcome the aforementioned disadvantages found in drafting machine constructions by providing an instrument chuck and wrench construction providing for the ready and secure engagement of the instrument with the drafting machine head and the ready disengagement of the instrument therefrom.

It is also an object of my invention to provide a drafting machine head employing a chuck receptacle adapted to frictionally receive a chuck member secured to an instrument to be used with the drafting machine head and a wrench for 5 forcing the chuck member into or out of the chuck receptacle.

It is a further object of my invention to provide an instrument chuck construction of the character set forth in the preceding paragraphs 10 which employs a chuck wrench for applying a wedging force between a chuck member and a chuck receptacle for forcibly inserting the member into the receptacle and for effecting the removal of the member therefrom.

It is also an object of my invention to provide a drafting machine construction of the character set forth in the preceding paragraphs wherein the chuck receptacle and chuck member are provided with opposed pressure faces and in which a chuck wrench is provided with a cam member engageable with said pressure faces to force the chuck member into engagement with the chuck receptacle and to forcibly withdraw the member therefrom.

It is also an object of my invention to provide a drafting machine head of the character set forth in the preceding paragraphs in which a tapered chuck receptacle is provided with an aperture and a tapered chuck member for insertion in said receptacle is provided with a slot disposable adjacent said aperture and in which is employed a chuck wrench having a portion engageable with said aperture and a pin member for engagement with said slot so that rotation of said chuck member will move said chuck member relative to said chuck receptacle.

Other objects and advantages of my invention will be apparent from a study of the following specification, read in connection with the accompanying drawing, wherein:

Fig. 1 is a plan view illustrating a well known form of drafting machine fitted with a drafting head employing an instrument chuck of my invention;

Fig. 2 is a fragmentary view representing a portion of Fig. 1 enlarged to show the details of construction of the chuck parts employed;

Fig. 3 is a perspective view showing one form of chuck wrench;

Fig. 4 is a fragmentary vertical section taken substantially along the line IV—IV of Fig. 2 to show the relative relationship between the chuck parts and the chuck wrench;

Fig. 5 is a diagrammatic view illustrating the

relative positions of the chuck members and the chuck wrench at the beginning of an operation to secure an instrument to the drafting machine head;

5 Fig. 6 is a schematic view similar to Fig. 5 but illustrating an intermediate portion of the operation; and

10 Fig. 7 is a view similar to Figs. 5 and 6 showing the relative disposition of parts at the time the instrument is firmly fixed to the drafting machine head.

15 Referring to the drawing, I have illustrated in Fig. 1 a typical drafting machine construction employing a parallel mechanism comprising a fixed supporting member 1 secured in any suitable fashion to the upper edge of a drawing board or working surface 2. The fixed support 1 pivotally mounts a parallel mechanism 3, illustrated in Fig. 1 as being of the endless band type which 20 employs a pair of pivotally jointed arms 4 and 5 which carry at their extremities pulleys enclosed by pulley guards 6, 7, and 8. These pulleys cooperate with a pair of endless bands 10 and 11 in a well known manner to maintain the drafting machine head 9 in a fixed angular position relative to the surface of the drawing board 2, while permitting translatory movement of the head 9 thereover.

25 The drafting machine head 9 of my invention 30 is provided in the preferred embodiment thereof with a scale supporting member 12 which may be detachably secured to the head 9 by means of suitable securing devices 13 and 14. The scale supporting member 12 preferably includes a pair 35 of arm sections 15 and 16 disposed at right angles relative to each other and adapted to carry various instruments, such as a scale 17 or a straight edge 18.

30 As illustrated in Figs. 2 and 4, each of the arms 40 15 and 16 of the scale supporting member 12 is provided on its under side with a chuck receptacle 19 communicating with the ends of the arm portions 15 or 16 and adapted to receive and frictionally retain a chuck member 22 secured to the scale 17 or other drafting instrument. Frictional retention of the chuck member 22 may be obtained by forming the chuck receptacle 19 with side wall portions 20 and 21 angularly disposed relative to each other to provide an elongated, tapered receptacle and by forming the chuck member 22 with a plate-like portion having opposed edge faces 25 and 26 which are angularly disposed relative to each other so as to provide a taper corresponding to the taper of the 55 side walls 20 and 21. It will be observed that when the chuck member 22 is tightly wedged within the tapered receptacle 19, its angular position relative to the drafting machine head 9 is fixed.

60 In order to permit angular adjustment of the instrument 17 relative to the head 9, I prefer to secure the chuck member 22 to the upper surface of the scale 17 by means of screws 23 and 24, the screw 24 passing through an elongated slot 27 in the chuck member 22 so that loosening of this screw will permit angular adjustment of the scale 17 relative to the chuck member 22 and so that tightening of the screws 23 and 24 will lock the scale in such adjusted angular position.

70 In order that the chuck member 22 may be forcibly inserted within the tapered chuck receptacle 19 and readily removed therefrom, I provide in the upper surface of the scale supporting member 12 a cylindrical bore 28 which 75 communicates with the upper surface of the

chuck receptacle 19. The diameter of the bore 28 is preferably made substantially the same as the diameter of a cylindrical shank portion 29 of a chuck wrench 30 which may include a T handle 31 disposed transversely of the shank 5 portion 29 and secured thereto.

I provide in the chuck member 22 an elongated slot 32 in a position to lie below the aperture 28 when the chuck member 22 is loosely inserted in the chuck receptacle 19. This slot is adapted to receive a pin portion 33 formed integrally or secured to the lower end of the shank portion 29 of the chuck wrench 30. The pin portion 33 is eccentrically disposed relative to the axis of rotation of the chuck wrench 30 so that as the 15 chuck wrench 30 is rotated about its longitudinal axis, the pin 33 will describe a small circle.

The operation of the chuck and chuck wrench of my invention may best be understood by having reference to Figs. 5, 6 and 7. At the time the 20 chuck member 22 is loosely or preliminarily inserted in the chuck receptacle 19, the parts will be disposed in the approximate positions illustrated in Fig. 5 with the slot 32 disposed near the outside edge of the circular aperture 28. The 25 chuck member 22 may then be forcibly engaged in the chuck receptacle 19 by inserting the chuck wrench 30 in such a manner that the pin portion 33 is received in the slot 32 and the shank portion 29 is received in the aperture 28. Rotation of the 30 chuck wrench 30 by means of the handle 31 will thereupon move the pin portion 33 through a circular path and tending generally inwards relative to the receptacle 19 so that the parts progressively assume the positions illustrated in Figs. 35 6 and 7.

It will be observed that the provision of the slot 32 for receiving the eccentric pin 33 permits the rotational movement of the pin 33 to impart a purely sliding or translatory movement of the 40 chuck member 22. When the parts are finally moved to a position corresponding to that illustrated in Fig. 7, the chuck member 22 has been moved inwardly within the receptacle 19 sufficiently far to forcibly engage the coacting tapered 45 surfaces and fixedly secure the chuck member 22 and the instrument 17 carried thereby to the drafting machine head 9. The removal of the instrument 17 from the drafting machine head 9 may be readily accomplished by reversing the 50 above described operation.

While I have described the preferred embodiment of my invention as employing a chuck wrench which includes a cylindrical shank adapted to be received in a circular aperture and a 55 circular eccentric pin adapted to be received in an elongated slot in the chuck member, it is to be understood that other shapes of coacting members may be used.

Attention is called to the fact that the chuck 60 wrench of my invention acts as a cam member between opposed pressure faces carried, respectively, by the scale supporting member 12 and the chuck member 22 to cause relative translatory movement between these members and 65 forcibly engage the member in the receptacle or move the member out of the receptacle, depending upon the direction in which the wedging force is applied.

It will be observed that I have provided a 70 simple and inexpensive instrument chuck construction adapted to be employed with an equally simple and inexpensive chuck wrench which provides for the ready, firm attachment of the instrument to the drafting machine head and 75

the equally ready removal of the instrument therefrom.

While I have shown and described the preferred embodiment of my invention, I do not desire to be limited to any of the details of construction shown or described herein, except as defined in the appended claims.

I claim:

1. In a chuck construction for use with drafting machines employing a scale supporting member, the combination of: a chuck member; a chuck receptacle formed in said scale support for receiving said chuck member; means in said chuck receptacle for frictionally retaining said chuck member; one pair of opposed pressure faces on said chuck member and on said scale support; and another pair of oppositely directed opposed pressure faces disposed on said chuck member and said scale support adjacent said one pair, whereby a chuck wrench having a wedging means may be interposed between both pairs of said opposed pressure faces and rotated to apply a wedging force therebetween to force said member inwardly and outwardly of said receptacle.
2. In a chuck construction for use with drafting machines employing a scale supporting member, the combination of: a chuck receptacle formed in said scale support; a chuck member insertable in said receptacle; means in said receptacle for frictionally retaining said member; an opening in said support communicating with said receptacle; and a recess in said member disposed in a position to be placed in overlapping relation with said opening when said member is inserted in said receptacle, whereby a wrench may be inserted through said opening and engaged with said recess and moved to bear against the sides of said opening and said recess to move said member inwardly or outwardly of said receptacle as desired.
3. In a chuck construction for use with draft-

ing machines employing a scale supporting member, the combination of: a chuck member; a chuck receptacle formed in said scale support for receiving said chuck member; means in said chuck receptacle for frictionally retaining said chuck member; a cylindrical bore through said scale support communicating with said chuck receptacle; and an elongated slot means in said chuck member disposed transversely of the length of said chuck member and disposed in a position to be placed below said opening when said member is inserted in said receptacle, whereby a chuck wrench having a cylindrical shank and a cylindrical pin eccentrically disposed on the end of said shank may be placed within said opening with said pin engaging said slot and rotated within said opening to apply a force to move said member inwardly and outwardly of said receptacle.

4. In a chuck construction for use with drafting machines employing a scale supporting member, the combination of: a chuck receptacle formed in said scale support having angularly disposed longitudinally extending side surfaces; a chuck member for reception in said chuck receptacle having tapered edge surfaces for engaging said side surfaces of said receptacle to secure said member therein; a cylindrical bore through said scale support communicating with said chuck receptacle; and elongated slot means in said chuck member disposed transversely of the length of said chuck member and in a position to be placed adjacent said bore when said member is inserted in said receptacle, whereby a wrench having a cylindrical shank and a pin eccentrically disposed on the end of said shank may be inserted within said bore with said pin engaging said slot and rotated to apply a force to move said member inwardly and outwardly of said receptacle.
